UNITED STATES PATENT OFFICE.

LEWIS MILLER, OF AKRON, OHIO.

GRAIN-BINDING HARVESTER.

SPECIFICATION forming part of Letters Patent No. 396,758, dated January 29, 1889.

Application filed January 16, 1886. Serial No. 188,778. (No model.)

To all whom it may concern:

Be it known that I, LEWIS MILLER, of Akron, county of Summit, and State of Ohio, have invented a new and useful Improvement in 5 Grain-Binding Harvesters, of which the following is a full, clear, and exact description, reference being had to the accompanying drawings, making part of this specification.

My invention relates, mainly, to the devices 10 for taking the grain from the delivery end of the platform-carrier and moving it across or over the inclined elevating-table to and packing it against the compressor preparatory to binding the same; and it consists in the combination, with the packer-actuating cranks or 15 crank-shaft, of a series of bars (two or more) having both picking or gathering and packing fingers for taking the grain from the discharging end of the platform-carrier and moving it up the inclined table to and packing it 20 against the compressor within the arc of the circle within which the needle moves, and a second series of cranks connected through said bars with and actuated from the packer 25 crank-shaft.

It further relates to the construction of the bars carrying the gathering and packing fingers and the manner of uniting them to their actuating-cranks, and to the combination, with said packing and gathering finger 30 bars, of a yielding float or spring-bar for holding the grain down to the action of the picking or gathering and packing fingers, and insuring the proper movement of the grain 35 thereby, as will be explained.

In the accompanying drawings, Figure 1 is a rear elevation, partly broken away, of a harvesting-machine with my improvements applied. Fig. 2 is a perspective view of a 40 portion of the binder-frame and inner end of the platform-carrier, with the binder-table removed to show the gathering and packing devices and their actuating-cranks; and Fig. 3 is a side elevation of one of the gathering and 45 packing bars and a portion of another with its removable half crank-box removed or detached. Fig. 4 is a perspective view of one of the crank-shafts which actuate the gathering and packing devices detached, showing 50 the arrangement of the cranks.

The machine, in its organization or general construction and arrangement of parts, is

similar to others in use and will not therefore be described in detail, except so far as is necessary to an understanding of the improvements herein claimed. 55

A indicates the main or platform frame; B, the main drive-wheel; C, the platform-carrier, and A' the standard-bracket in which the rear end of the outer longitudinal bar, D, 60 of the binder-frame is supported, a similar or other suitable standard, A², serving to support the bar D from the inner end of the forward-platform sill, the inner ends or extensions of the front and rear platform frame 65 sills, in connection with the standards A' and A² and bar D, with suitable inclined transverse bars which serve to support the inclined elevating-table F, forming a triangular frame, within which, between the inner 70 end of the platform-carrier C and the plane of the inner face of the drive-wheel B, the picking or gathering, packing, and binding devices and their actuating mechanism are arranged, as hereinafter described. 75

The standard A' is provided with a bearing for the rear end of the main binder-gear shaft a, which has further bearings in suitable brackets on the binder-frame or in the forward outer standard-bracket in a manner well understood, and receives motion from the main drive-wheel through a bevel-wheel gearing with a bevel-wheel on the secondary or pinion shaft, as indicated, or in any suitable manner. The shaft a is provided with cranks 80 a' a², arranged, preferably, in pairs—a central pair with space for the needle between the bars b b' or packers actuated by them and other pairs in front and in rear of said central pair for acting on the butts and heads of 85 straw or grain. 90

The shaft a has secured to it a spur gear or pinion, a³, which engages and drives a similar gear, c', fast on a longitudinal shaft, c, mounted in suitable bearings on the main frame a, and having on its forward end a crank or crank-wheel, from which motion is communicated to the knife-bar, and on its rear end one or more sprocket-wheels, from which motion is communicated to the platform-carrier 95 and other operative parts of the machine in any suitable manner. 100

D' and D² are two inclined bars connected by sleeves d, at their upper ends, with the

packer crank-shaft *a*, and by sleeves *d'*, at or near the center of their length, with the shaft *c*. These bars extend beyond the shaft *c* toward the platform-carrier, and are provided at their ends adjacent to said carrier with sleeve-bearings *d²*, in which a second packer crank-shaft, *e*, having cranks *e'* *e²*, is mounted, to the cranks of which the lower ends of the bars *b* and *b'* are attached.

10 The shaft *e* may have other bearings than those described, if desired, for supporting them from the harvester-frame, its flooring, or other suitable point; but those referred to have been found sufficient in practice, as they serve to prevent relative lateral movement of the shafts *a* and *e*, connected by the bars *b* *b'*, which is important, as the shaft *e* receives its rotary movement from the shaft *a* through the series of connecting-bars *b* and *b'*.

15 The bars *b* and *b'* are made arching in form between the points of attachment to the shaft *a* and *e* for a double purpose—viz., to adapt them to conform to the movements of the cranks on said shafts, and at the same time swing clear of and above the intermediate shaft, *c*, and to adapt them in such arched portion to pass up through the slots in the inclined binder-table *F*, and so to present an extended surface, which shall act upon the

20 grain upon said table to lift it bodily and move it upward over the table toward the compressor *G*, relieved from the frictional resistance of the surface of the table to such upward movement. These bars are provided

25 at their upper ends with fingers *b²*, which act as packers, moving within the arc of the circle described by the needle for packing the grain, and at their lower ends with outwardly-projecting curved fingers *b³*, the points of

30 which, in the outward and upward throw of the cranks actuating the bars, move in close proximity with the delivery end of the platform-carrier outside of the arc of a circle in which the needle moves and serve to gather

35 or pick up the grain therefrom and to move it upward on the lower portion of the inclined table *F*, and between the fingers *b²* and *b³* the bars *b* and *b'* are provided on their upper arched faces or edges each with one or

40 more short intermediate fingers, spurs, or teeth, *b⁴*, which serve to prevent the grain from slipping backward while it is being carried upward over the table by such arching portions of the bars. These intermediate

45 spurs or teeth, *b⁴*, being made short, are withdrawn below the inclined table before the gathering-teeth *b³* are, and so permit the grain to roll back against the latter and thereby to become detached or separated from the grain

50 being bound and to accumulate to form a new bundle.

The bars *b* and *b'* are made of thin metal, flanged on their lower concave edges to give them the requisite stiffness and strength without unnecessary weight of material, and have

55 half-boxes formed in their ends where they

connect with their actuating-cranks, removable half-boxes *b⁵* and suitable screws or short bolts serving to unite them to said cranks. The cranks of each pair of bars are set opposite each other, so as to make said bars and their fingers act alternately; but those at the front and rear are set, preferably, at an angle of about ninety degrees to those of the central pair to cause the bars to act intermediate of those of the central pair, and thereby to make them practically continuous in their actions, which will be readily understood without further description.

II indicates the knotter-shield, the inner or lower end of which is attached to and upheld by the picker-supporting bar *H'*, and to said end is secured a bar, *h*, which projects over the inner or delivery end of the platform-carrier and has a curved bar or plate, *h'*, forming a "float" hinged to its outer end, said float extending inward over the inner end of the platform-carrier and the adjacent lower side of the inclined elevating-table, as shown, and serving by its weight or elasticity, either or both, to hold the grain passing off the delivery end of the carrier and upward on the inclined table down lightly to the action of the gathering-fingers and the bars to which said fingers are attached and to insure its movement up to the action of the packing-fingers. The bar or float *h* has its inner end upheld at any desired height above the table by means of an adjusting-rod, *h²*, connected thereto with its upper end passing through a perforation in the bar *h* and upheld by a pin passed through any one of a series of holes in its upper end above the bar *h*. A light coiled spring, *h³*, surrounding the rod *h²* between the arm or bar *h* and the float *h'*, serves to hold the latter down to its work with the required pressure.

The bar *H* has pickers or gathering-fingers *I* *I'* connected with it, to which motion is imparted in any usual manner for causing them to assist in picking the grain off the delivery end of the platform-carrier and moving it up the foot of the inclined table and within the reach and action of the other picking grain-moving devices described.

Parts of the machine not specifically described may be of any usual or preferred construction and arrangement.

Having now described my invention, I claim as new—

1. The combination, with the slotted binder-table, of parallel crank-shafts, arched bars connected to cranks on said shafts to pass through the table and act on the grain thereon, and picker or gathering and packing fingers on said bars, substantially as and for the purpose described.

2. The inclined and slotted elevating binder-table and the crank-shafts underneath said table, in combination with arched bars connected at their opposite ends to cranks on said shafts to pass through said table, and the

picker and packer fingers on said bars, also passing through the table, all substantially as described.

3. The combination, with the needle, of the arched bars carrying gathering and packing fingers, and operating on opposite sides of and in close proximity to the plane of said needle, the parallel crank-shafts having oppositely-arranged cranks in pairs for operating said bars to act alternately on the straw, and oppositely-arranged intermediately-acting cranks, carrying also curved bars having gathering and packing fingers and acting on the ends of the straw, substantially as described.

4. In combination with the slotted binder-table, the needle or needle-guard, the crank-shafts, and the bars connecting said shafts provided with pickers or gathering fingers and packers, and with spurs arranged between the gathering-fingers and packers, and made short for the purpose of releasing the grain and permitting a rolling motion thereof between the packers and gathering-fingers, substantially as described.

5. The combination, with the slotted binder-table, needle, and compressor, of the parallel crank-shafts, and the arched bars connecting the cranks on said shafts and pro-

vided with pickers or gathering-fingers and packers, and the intermediate spurs made shorter than the gathering and picking fingers, all substantially as and for the purpose described.

6. The frame-work supporting the binder-table, in combination with the parallel crank-shafts located underneath said table for operating the gathering-fingers and packers, and the bars or braces connecting said shafts, and in the ends of which said shafts are journaled, substantially as described.

7. The combination, with the inclined elevating binder-table, of the parallel crank-shafts located underneath said table, the connecting bars or braces in which said shafts have their bearings, said bars being provided also with bearings for the crank-shaft actuating the knife-bar, and the arched bars carrying the gathering-fingers and packers connected to and operated by said parallel crank-shafts, substantially as described.

In testimony whereof I have hereunto set my hand this 24th day of December, A. D. 1885.

LEWIS MILLER.
